UNITED STATES PATENT OFFICE.

EMMET SMITH PALMER, OF SEATTLE, WASHINGTON.

LOCKING MEANS FOR THE BOLT SYSTEM OF VAULT OR SAFE DOORS OR THE LIKE.

Application filed March 16, 1920, Serial No. 366,197. Renewed April 2, 1923.

To all whom it may concern:

Be it known that I, EMMET SMITH PALMER, a citizen of the United States, residing at Seattle, in the county of King and State of Washington, have invented a certain new and useful Improvement in Locking Means for the Bolt System of Vault or Safe Doors or the like, of which the following is a specification.

10 My invention relates to the art of locking means for the bolt system of vault or safe doors, or the like. More particularly my invention relates to the providing of a new and positive defensive system for vault doors rendering the same in and of themselves self sufficient in resisting unauthorized manipulation, and providing for the reopening thereof.

As vault doors and vault door bolt systems 20 have been heretofore designed, the usual method or practice in gaining unlawful entrance to the vault is to destroy violently or violently tamper with the combination lock. This destruction of the lock is achieved by 25 blowing out or driving thru the operating mechanism and when this is done the bolt system is free to be moved into unlocked position. Electrically charged conductors distributed over the inner walls of a vault 30 door to prevent unauthorized entrance have been employed to give an alarm, i. e. a "cry for help." Objection to such construction is that it does not make the vault-door self-sufficient in and of itself to resist such unauthorized entrance and hence, as often happens much damage is done before "help" arrives.

The objects of my invention are to provide 35 a magnetically operated locking means which will automatically lock for a predetermined time the bolt system upon the destruction or violent tampering with the combination lock, and which will automatically unlock the said bolt system at the end of that time. I purpose rendering a vault or safe door or the like self sufficient in and of itself in resisting unlawful entrance. A primary object of my invention is to provide such a bolt system locking means that is simple and may be readily applied to vault or safe doors or the like of various makes and designs and to these, after installation as well as at the time of manufacture of said vaults, safes or the like. Moreover, it is my 50 object to provide such a bolt system locking means which is capable of using an electro-

magnet of such power, that provision is made for the automatic unlocking of the same with certainty at a time desired, and to provide a bolt blocking means or latch of such form 60 that its movement is free for certain and full engagement with the bolt. Besides these a further primary object of my invention is to provide a bolt system locking means which will automatically lock the said system whenever the bolts are moved into locked position and which locking means is unlocked by means of an electro-magnet operatively connected with a combination lock. Also I purpose providing such a bolt system locking 70 means that any attempt to burn or drill thru the plate of the vault door for any purpose will result in locking the bolt system just as does the removal or tampering with the combination lock. 75

The above mentioned general objects of my invention together with others inherent in the same are attained by the mechanism illustrated in the following drawings, the same being merely preferred exemplary 80 forms of embodiment of my invention, throughout which drawings like reference numerals indicate like parts:

Figure 1 is a view of a preferred form of my invention as respects the emergency lock in its application to a common design of vault door—a front view of the inner side of which is shown; 85

Figure 2 is a transverse sectional view of said vault door, further showing the application of my invention; 90

Figure 3 is an enlarged detailed front view of the eccentric latch member pivotally mounted, and the bolt and electro-magnet associated therewith; 95

Figure 4 is a vertical sectional view on broken line 4, 4 of Fig. 1 showing one means of connecting the switch to the combination lock;

Fig. 5 represents a modified form of a latch, namely a lever latch attached directly to the bolt frame; 100

Fig. 6 is a perspective view of a modified form of bolt-blocking means and its location in a vault vestibule; 105

Fig. 7 is a plan view of said modified form of bolt-blocking means;

Fig. 8 is an enlarged front view of the same;

Fig. 9 is a detail view of a cable-trigger means on the combination lock; 110

Fig. 10 is a detail view of the spring switch and attached cable;

Fig. 11 is a front view of a modified form of my invention electrically connected to the combination lock designed as a night lock;

5 Fig. 12 is a side view of the combination lock of such modified form showing its electrical connections;

Fig. 13 is an enlarged detail view of the combination lock of such modified form 10 showing its electrical contact in open position;

Fig. 14 is a front view of still another modified form of my invention showing bolt locking means, i. e., the emergency lock 15 below and the night lock above applied to the same bolt;

Fig. 15 is a view in transverse section; showing the protective plate insulated from the door plate; and

20 Fig. 16 is a view of a switch operatively connected to one of the bolts whereby a circuit is automatically open and closed.

The general arrangement and disposition of the parts of the preferred form of my invention, as respects the emergency lock are 25 shown in Figs. 1 and 2. The combination lock 17 of a conventional vault door 18 controls through parts 19 and 20 (Fig. 1) the bolts 21 of the bolt system, said bolt 30 system being operatively controlled by the bolt-throw handle 22. A cable 23 has one end 24 looped, i. e. provided with an eye, (Fig. 4) and secured over a pin 25 made fast to the combination lock-block or housing 26. Said cable 23 preferably passes 35 squarely, i. e. centrally over the lock back plate 27 forming thereby a "trigger" means to "set off" the locking means. The other end 28 of the cable 23 is secured to the 40 blade 29 of a knife switch 30. Opposed to said cable 23 is the spring 31, which insures a positive closing of the switch 30 when the cable 23 is released from the pin 25. Since 45 said spring 31 is attached to the bolt frame member 38, it serves to ground the circuit. Electric wire 32 connects post 33 of switch 30 with battery 35 which is connected by wire 34 to electro-magnet 36 and this in turn is grounded by wire 37 to the bolt 50 frame 38 which carries the bolt system. Near the core 39 of the electro-magnet 36, the emergency eccentric latch member, i. e. bolt blocking member, 40 (Fig. 3) is pivotally mounted on pin 41 with the curved side 55 42 of one of its arms normally (i. e. unlocked position) nearest the said core member 39 and its straight side 43 nearest the bolt 21. The difference in the length of the sides of this arm thus causes said arm to 60 have an "eccentric" movement with respect to the core 39. A notch 44 in the bolt 21 receives the end 45 of the latch 40 when the electro-magnet is energized and the latch rotated on its pivot pin 41. A ring block 46 65 fits about the bolt 21 and preferably pre-

sents an inclined face 47 as a bearing to the latch end 45 when moved into locking position.

To prevent drilling or burning a hole through the door plate 48, a modified form 70 of a "trigger" means, i. e. a protective plate 49, is caused to extend over the inner surface of the door plate 48 as an inner lining and is insulated and separated therefrom with insulation 50. Electric wire 51 connects the 75 protective plate 49 to the post 33. A drill bit or metal from burning of the door plate 48 would complete the circuit and cause the energizing of the electro-magnet 36 and therefore the locking of the bolt 21 just 80 as would releasing the cable 23 from the pin 25 by violent tampering with the combination lock housing 26.

It will be understood that upon locking one of the bolts 21, all of the bolts of the 85 system are locked. When the vault door 18 is closed, the bolt 21 before the bolt-throw handle 22 is operated, swings back of the angle iron 52 on the side having the hinge 53 to the point shown in dotted line 54. By thus extending so far back, the bolt 21 clears 90 the angle iron 55 on the front side. Then when the bolt-throw handle 22 is turned, the bolt 21 is moved forward as shown in solid lines as illustrated, so that the bolt 21 extends behind both angle irons 52 and 55. The inner vestibule doors 56 and 57 are 95 shown in closed position. An electric signal bell 58 may be connected with the switch 59 by electric wire 60 and to the said bell's 100 separate battery 61 by wire 63. Wire 62 completes the circuit between the switch 59 and the battery 61. This bell is set ringing when the latch 40 is caused to move into locking position, said latch member 40 being provided with a hard-rubber bumper 64 which 105 operates to press an electric switch spring 65 into contact with a plate 66, so that notice may be given to the would be unauthorized entrants that emergency locking 110 means within has been actuated and that their further efforts are rendered useless.

The modified form of bolt blocking means, i. e. latch 67 shown in Fig. 5 is more simple 115 in construction and constitutes a lever form of latch pivotally mounted on the side of the bolt-frame member 38. This form of latch is my preferred form for the ordinary fire proof vault door. This latch 67 enters notch 68 in the bolt and bears directly against the bolt-frame member 38 when in locked position and an attempt is made to force back the bolt 21. A switch 69 is closed when the latch 67 moves into closed position and thereby the signal bell 58 is caused to ring.

120 In the modified form, shown in Figs. 6, 7, 8, and 9, a cable 70 enclosed in a flexible casing 71 connects the combination lock housing 26 with the electric switch 30, said cable being looped at one end 24 to pass over 125

a pin 72 located on top of the combination lock housing 26. The other end 28 of the cable 70 is secured to the blade 29 of the switch 30. The spring 31 secured to said blade 29 keeps the cable under tension and insures a positive closing of the switch 30 when the cable 70 is released from the pin 72. The switch 30 is electrically connected to the electro-magnet 36, operatively mounted as in the first instance with respect to the eccentric member 73 which is provided with a block 74 adapted to be moved up behind the bolt 21 so that said bolt cannot be moved back to enable the front portion to clear the angle iron 55 as said block nearly fills the space behind said bolt 21.

The bolt-locking means heretofore described are designed solely to block the bolt system in an emergency, i.e. upon destruction or violent tampering with the combination lock housing 26 or back plate 27. In Figs. 11 and 14 are shown bolt locking means designed to lock the bolt system nightly by means supplementary to the combination lock, i. e. voluntarily or on occasions other than emergencies. Besides the emergency eccentric member or latch 40 there is provided a night lock eccentric member 75 and a notch 76 in the bolt 21 illustrated separately in Fig. 11 so as not to be confused with the emergency eccentric 40 which, however, is shown in association Fig. 14. An electro-magnet 77 exerts its force upon said night lock eccentric member 75 which is electrically connected to the regular combination lock mechanism 78 using the signal bell's circuit, i. e. using a circuit separate from the emergency latch 40.

The disks 79, 80, 81, and 82 of the combination lock 17 are flattened on one side as at 83, so that a transverse bar 84 in a recess 85 on the upper side of the lock housing 26 may descend and cause the plate 86 electrically connected with the electro-magnet 77 and fixed to said bar 84 to descend. Insulation 87 between the said bar 84 and the said plate 86 separates the two electrically. When the plate 86 descends and makes contact with the housing 26, the circuit is completed by thus grounding it. A stud 88 fixedly secured on the emergency eccentric or latch 40 extends upwardly so as to engage the night lock eccentric member 75 and lift it out of engagement with the notch 76, causing said eccentric member 75 to rotate sufficiently to throw the center of mass to the right of the vertical line thru the pivot point 89 of the said eccentric 75. In order that the electric circuit of the night lock eccentric 75 or any other circuit herein may be automatically opened and closed, a knife switch blade 90 is pivotally mounted at 91 to the bolt frame 38 and pivotally connected at 92 to the bolt 21, so that when the bolt 21 is moved back and forth it will make and 65 unmake contact with the point 93.

The mode of operation of my device is as follows: Upon closing the vault door, the bolts 21 are caused to extend behind both of the angle irons 52 and 55 by turning the bolt-throw handle 22, in which position they are shown in Fig. 2. After thus "throwing" the bolt system, the combination lock 78 is moved out of register so that thereafter the bolt-throw handle 22 cannot be turned to withdraw the bolts. To move the bolts, the combination of the combination lock 17 must be known and the disks set in register or the said lock with its housing 26 must be destroyed. Assuming that unauthorized entrance to the vault is attempted by destroying the combination lock 17, as is the usual method so as to render the bolt-throw handle free to be turned, it is manifest that any tampering with the combination lock 17 either by blowing or driving out the operative parts 78 of the same, will displace the back plate 27 which will release the cable 23 from the pin 25 which parts thus function as a "trigger" means. Thereupon, 90 spring 31 snaps the switch blade 29 into closed position, and hence, by grounding closes the electric circuit of the electro-magnet 36 which causes the emergency latch 40 to rotate until the end at the upper side, i. e. 43 comes into contact with the core 39, i. e. the end 45 of the latch is moved into engagement with notch 44 where it is held so long as the electro-magnet 36 is energized and thereby prevents the backward 100 movement of the bolt 21, so that the bolt system cannot be moved into unlocked position. The end 45 of the latch or bolt blocking member 40 is caused to bear against the inclined face 47 of the block 46, which thus insures a firm blocking of the bolt 21 against transverse movement. When the battery 35 is exhausted, the latch 40 falls by force of gravity, from engagement with notch 44 and then the bolt-throw-lever 22 can be 110 operated to withdraw the bolts 21. This period when the battery 35 will be exhausted can be predetermined so as to permit of opening the vault doors at such time as it will be safe, i. e. after the attempted unauthorized entrance has been foiled, and the books, money, and other valuables may then be available for the day's business. Since 115 electro-magnets are usually wound to use as little current as possible, it would require too long a time to exhaust the ordinary standard battery. Experiment has taught that it is preferable as batteries are made of standard strength, to use specially wound electro-magnets designed to use a large current. I preferably employ the exhaustive method of unlocking the emergency bolt lock as it offers no exterior avenue of en-

trance as would a combination lock or secretly hid button. By providing for the removal of the force which maintains the latch in locking position, preferably and as herein shown by exhausting the battery, provision is made for the positive and certain withdrawal of the latch—preferably and as herein shown, the force of gravity is caused to co-operate with said exhausting 10 of the battery.

The advantage of the eccentric character of the latch 40 will now be manifest. The latch must be rotated sufficiently to lock the bolt and to do this the latch must not at 15 first come into contact with the core 39, because otherwise it would stop rotating before making engagement with the notch 44. By providing the eccentric form, the contact with the core 39 is not made until full 20 engagement with the said notch 44 is made and then when contact is made, it requires but small magnetic force to hold the eccentric member in engagement with the notch 44 so that a positive and certain locking 25 of the bolt is assured. The greatest magnetic force is demanded at the beginning when the electro-magnet must act thru space to actuate the latch and this is when the battery has its maximum strength. As 30 the battery approaches exhaustion, there is no danger of prematurely unlocking as little magnetic force is then required since the latch is then in contact with the core 39 and a small magnetic force is sufficient 35 to hold the latch in locking position. Therefore, unlocking occurs only when the battery is almost wholly exhausted. Shortening the distance between the core (39) and the latch (40) would have the same effect 40 in principle even though actual contact is not made.

Again if unauthorized entrance thru the vault door is attempted by burning a hole thru the door plate 48 with an oxyacetylene 45 burner, or by drilling, it is clear that contact will be made with the protective plate 49 which will cause the energizing of the electro-magnet 36 and the locking of the bolt 21 just as does the releasing of the 50 cable 23 from its pin 25 i. e. the other "trigger" means. Establishing electric connection between protective plate 49 and door plate 48 is but another means of grounding the circuit in place of the spring 31 functioning as a conductor for such purpose. In this manner the usual method of gaining unauthorized entrance to a vault by destroying the combination lock is positively 55 precluded. The vault door is thus made in and of itself burglar proof as contrasted with the devices which rely upon setting off an alarm and the calling in of defenders.

The purpose of the signal bell 58 has been hereinabove set forth. However, just 60 as said bell's circuit was closed so could the

circuit of one of the many common and well known types of alarm bells (not shown) or systems be closed, so that an alarm could be turned in.

The operation of the modified form shown 70 in Figs. 6, 7, 8 and 9 will now be readily understood. The cable 70 corresponds to the short cable 23, functioning as a trigger means as does said short cable. The blocking means or eccentric member 73 does not 75 enter a notch in the bolt 21 but is provided with a block 74 which fills the space behind the said bolt 21 when the eccentric member 73 is actuated. It will be noted that any attempt to burn thru the door plate 48 will 80 also burn the casing 71, severing the cable 70 and thereby locking the bolt 21 just as does the releasing of the said cable 70 from the pin 72.

In the modified form where the bolt system is locked nightly, the eccentric 75 rests upon the bolt and falls by gravity into locking position when the bolt 21 is moved transversely into locking position. The electro-magnet 77 controlling the eccentric 75 is 90 subject to electric control by the combination lock 78 having specially provided electrical connections hereinabove named and set forth, or subject to control by a separate combination lock whose sole function 95 is to operate said eccentric 75 by lifting it into unlocked position. I preferably provide an emergency eccentric 40 just below said night lock latch 75. When the emergency latch 40 is actuated it pushes by means 100 of stud 88 the night latch 75 out of engagement with the bolt 21 and itself engages said bolt. The stud 88 strikes the latch 75 near its pivot point 89 so as to allow a small vertical movement on the part of said stud 105 88 to effect a relatively large displacement of the said latch 75 and cause its center of mass to rest finally to the side of the vertical line thru the pivot point 89 oppositely disposed to the notch 76. Thus, when the 110 emergency latch 40 falls out of locking engagement with the notch 44 upon exhaustion of the battery 35 the bolt 21 is free to be moved into unlocking position since the night lock latch 75 is also disengaged. 115

In general, thus it will be seen:

First, I provide a bolt blocking means, in one of the forms of a latch designated as 40, 67, 73 or 75, which prevent the withdrawal of the bolts of the bolt system; second, means to actuate this bolt blocking means, such as the electro-magnet; third, "trigger" means which "sets off" the electro-magnet, such means being the cable 23, 70 or the protective plate 49; fourth, provision 120 for automatically unlocking the mechanism consisting in exhausting the battery which supplies the electromagnet with power. Furthermore, in conjunction with said 125 exhausting of the battery I preferably utilize 130

gravity as an unlocking means on account of the simplicity of the construction incident thereto and because of its certainty of operation—the unlocking must be effected 5 with absolute certainty; and fifth, while that next preceding relates particularly to a bolt blocking or locking means which is not controllable exteriorly so far as the unlocking part is concerned, i. e. pertains to 10 an emergency lock, I also provide such a locking means which coacts and operates in conjunction with said emergency lock but is controllable, so far as the unlocking is concerned (if the emergency lock has not 15 assumed the duty of locking the bolt) from the outside.

Obviously, changes may be made in the forms, dimensions, and arrangement of the parts of my invention, without departing 20 from the principle thereof, the above setting forth only a preferred form of embodiment.

I claim:

1. A locking mechanism for a vault door 25 bolt system embodying a bolt blocking means, an electromagnet operatively disposed with respect to said bolt blocking means, a switch, a combination lock, and a connecting means, one end of which is releasably secured to the combination lock and the other end of which is secured to said switch which is thereby maintained normally in open position.

2. A locking mechanism for a vault door 35 bolt system, embodying a bolt blocking member, means connecting the combination lock of said door and the said lock blocking member, an electrical conducting plate connected to and insulated upon said vault 40 door, and electric means connecting said plate with said bolt blocking member whereby injury to or tampering with said combination lock of said vault door or said plate actuates said bolt blocking member 45 into locking position.

3. A locking means for a vault door bolt system embodying a latch disposed to engage one of the bolts of said system, an electro-magnet operatively disposed with respect to said latch, a spring operated switch, a combination lock a cable, one end of which is releasably secured to the combination lock and the other end of which is secured to said switch which is thereby 55 maintained normally in open position.

4. A locking mechanism for a vault door bolt system, embodying a bolt system, a latch disposed to engage a member of said system, an electromagnet operatively disposed on an open circuit with respect to said latch, a combination lock and trigger means connecting said electromagnet to said combination lock.

5. A locking mechanism embodying a bolt, a latch disposed to engage said bolt

and normally held in disengaged position, an electromagnet operatively disposed with respect to said latch, a combination lock, and means connecting said electromagnet and said combination lock whereby said electromagnet may be caused to move said latch into locking position and maintain the same in said position for a predetermined period, upon the expiration of which said latch is moved into unlocking position. 70

6. In combination with a vault door locking mechanism, a bolt system, a latch operatively disposed to engage a member of said system, said latch being normally held in unlocked position, an electromagnet disposed to actuate said latch, a combination lock, and means connecting said combination lock and said electromagnet whereby said electromagnet may be caused to move said latch into locking position and maintain the same in said position for a predetermined period, upon the expiration of which said latch is moved into unlocking position. 75

7. A locking mechanism for a vault door 90 bolt system embodying a bolt system, an emergency latch, disposed to engage a member of said system, an electromagnet which actuates said latch, a combination lock, trigger means connecting said electromagnet to said combination lock, a night lock latch disposed to engage one of the members of said system, and an electromagnet electrically connected to said combination lock. 95

8. A locking means for a vault door bolt 100 system embodying an emergency latch, disposed to engage one of the bolts of said system, an electro-magnet which actuates said latch, a combination lock trigger means connecting said electro-magnet to the combination lock of said vault door, a night lock latch disposed to engage one of the bolts of said system and an electro-magnet electrically connected to said combination lock. 105

9. In combination with a locking mechanism for a vault door bolt system, a pivoted latch having an arm, said arm having one side straight and the other side curved whereby said arm may be caused to move through a predetermined length of arc. 110

10. A locking mechanism for a vault door bolt system embodying an emergency latch, disposed to engage one of the bolts of said system, an electromagnet which actuates said latch, trigger means connecting said electromagnet to the combination lock of said vault door, a night lock latch disposed to engage one of the bolts of said system, an electromagnet electrically connected to said combination lock, and means which automatically disengages said night latch when said emergency latch moves into locking position. 120

11. In combination with a locking mechanism for a vault door bolt system, a com- 125

bination lock having its discs flattened on one side, a transverse bar contacting with and movably disposed with respect to said discs, and an electrical conducting plate insulatedly mounted on said bar, said plate being disposed to make contact with the housing of said combination lock.

12. In combination with a locking mechanism for a vault door bolt system, a combination lock having its discs flattened on one side, a transverse bar contacting with and movably disposed with respect to said discs, an electrical conducting plate insulatedly mounted on said bar, said plate being disposed to make contact with the housing of said combination lock, a latch disposed to engage a member of said bolt system, an electromagnet operatively disposed with respect to said latch, and an electric means connecting said electromagnet and said plate mounted on said bar.

13. In combination with a locking mechanism, a night latch, an emergency latch, an electro-magnet disposed to actuate said emergency latch into locking position and means which automatically moves said night latch into unlocked position when said emergency latch moves into locking position. 25

14. In combination with a locking mechanism, a night latch, an emergency latch disposed beneath said night latch, electromagnets operatively disposed to actuate said latches into locking position and means which automatically moves said night latch 30 into unlocked position when said emergency latch moves into locking position. 35

In witness whereof, I hereunto subscribe my name this 10th day of March, A. D. 1920.

EMMET SMITH PALMER.
